No. 894,973.

PATENTED AUG. 4, 1908.

D. F. MORGAN.
MOISTURE ABSORBER.
APPLICATION FILED MAR. 17, 1908.

UNITED STATES PATENT OFFICE.

DANIEL FRANCIS MORGAN, OF JACKSON, OHIO.

MOISTURE-ABSORBER.

No. 894,973.

Specification of Letters Patent.

Patented Aug. 4, 1908.

Application filed March 17, 1908. Serial No. 421,626.

To all whom it may concern:

Be it known that I, DANIEL FRANCIS MORGAN, a citizen of the United States, residing at Jackson, in the county of Jackson and State of Ohio, have invented a new and useful Moisture-Absorber, of which the following is a specification.

This invention relates generally to moisture absorbers, and more particularly to one of that class employed for removing the moisture from the atmosphere of rooms in a building.

The object of the invention is to provide a device of this character which shall be simple of construction, shall be portable; shall be capable of being suspended from an overhead support, or of resting upon the floor of a room, shall be readily permeable by air, thus to cause the hygroscopic agent employed to have the maximum of efficiency and rapidity of action, shall be adapted for ready recharging, when necessary, and for the removal of the precipitated moisture without causing the latter to contact with the absorbing agent, and which will be durable and capable of long continued use without danger of derangement or deterioration.

With the above and other objects in view, as will appear as the nature of the invention is better understood, the same consists, generally stated, in a moisture-absorbing device embodying a gridded or openwork container for the hygroscopic agent, and a support therefor constituting a water trap or pan, the latter being provided with means to permit ready discharge of the condensed moisture without subjecting it to contact with the absorbing agent.

As a means for transporting the device, a suitable bail or handle is provided, and this is furnished with an eye or loop, whereby the device may be suspended from the ceiling of a room, or from an overhead support where it is desired that the absorption of the moisture shall take place above the floor of the room.

Further and more specific details of construction and points of novelty of the invention will hereinafter be fully set forth.

In the accompanying drawings forming a part of this specification, and in which like characters of reference indicate corresponding parts, Figure 1 is a view in side elevation, partly in section, of one form of moisture absorbing device embodying the features of the present invention. Fig. 2 is a horizontal sec-

tional view, on a reduced scale, taken on the line 2—2 of Fig. 1, and looking in the direction of the arrow thereon. Fig. 3 is a view in side elevation, partly in section, of a modified form of the invention. Fig. 4 is a fragmentary detail sectional view of a portion of the device.

The device shown in Figs. 1 and 2 comprises a container 1 for the hygroscopic agent, which may be in substance suited to the purpose, such as calcium chlorid, and a support therefor embodying a ring or annulus 2 having a beaded edge, a drip pan 3, and a plurality of bars or ribs 4 connecting the drip pan and the ring. The container 1 may be constructed of reticulated metal fabric, as shown, or of foraminous sheet metal, as may be preferred, and has secured to its upper edge, in any preferred manner, two bands 5 to the inner one of which is secured a plurality of catches 6 that are adapted to rest upon the beaded edge of the ring and thus sustain the container in proper position relatively to the drip pan 3, which, as shown in Fig. 1, is of sufficiently greater diameter than the container to insure the catching and retention of the condensed moisture that escapes from the hygroscopic agent held in the container. The ribs 4 are herein shown as approximately rectangular in cross section, although this is not absolutely essential, and their ends are secured to the ring and to the drip pan by rivets 7. The drip pan is provided with a suitable spout 8 by which the water may be removed therefrom.

In order to facilitate transportation of the device, a suitable bail or handle 9 is provided, which is connected with the ring through the medium of headed studs or pins 10. The intermediate portion of this bail is provided with an eye or loop 11 by which it may be suspended from an overhead support. As will be obvious, the container 1 may readily be removed from the ring 2 for the purpose of cleansing when necessary, or for any other reason.

In the form of the invention shown in Fig. 3, the container is of substantially the same construction as that above described, but, instead of employing the ring 2, drip pan 3, and ribs 4, a bucket 12 is used, the same being provided with any desired number of ori- fices 13 that extend below the lower end of the container, thus to insure proper circulation of air through the device, and its subjection to the absorbing agent. The bottom

portion of the bucket or support 12 is provided with a suitable spout 14.

In using either of the devices shown, after the container has been supplied with the absorbing agent, it is placed at any desired point in a room, and as the moisture is absorbed and condensed, it will escape through the meshes or openings of the container, and pass to the bottom of the support, whence it may readily be removed. As will be seen by reference to Fig. 3, the container 1 is of sufficiently less diameter than the support or bucket 12 as to insure free circulation of air around the entire exposed surface of the container.

The hygroscopic agent may be a divided mass, or may be in large lumps, as may be preferred, and as it deliquesces, the smaller particles will escape through the openings of the container and fall to the bottom of the support, whence they may readily be removed.

It will be seen from the foregoing description that although the improvements herein described are simple in character, they will be thoroughly efficient for the objects designed and capable of application for use in a variety of positions.

I claim:—

1. A device of the class described comprising an openwork support, an openwork container arranged therein and being of less di-

ameter than the support, a band secured to the upper portion of the container, a plurality of catches secured to the band and arranged to engage the upper edge of the support, and a bail or handle connected with the support.

2. A device of the class described comprising a support embodying an annulus, a drip pan, and a plurality of ribs connecting the annulus and pan, a container arranged within the support, a band secured to the upper portion of the container, a plurality of catches carried by the band and arranged to engage with the annulus, and a bail or handle connected with the annulus.

3. A device of the class described comprising a support embodying an annulus, a drip pan, and a plurality of ribs connecting the annulus and pan, a container arranged within the support and being of less transverse diameter than the same, a band secured to the upper portion of the container, and a plurality of catches carried by the band and arranged to engage with the annulus.

In testimony that I claim the foregoing as my own, I have hereto affixed my signature in the presence of two witnesses.

DANIEL FRANCIS MORGAN.
